HIGH-PRESSURE PUMP

Martin Wells, Los Angeles, Calif.

Application July 16, 1945, Serial No. 605,247

7 Claims. (Cl. 103—174)

1

My invention relates to high pressure hydraulic pumps such as employed with hydraulic presses for applying high pressure hydraulic fluid to the cylinders of said presses after the presses have been substantially closed by low pressure fluid.

Pumps of this general character for developing pressures of from three to six thousand pounds per square inch have been relatively expensive owing to the difficulty of making a pump of this type which is dependable and which will operate for a reasonable period of time. An object of my present invention is to provide a high pressure pump of extremely simple construction which will operate at high pressures such as required in hydraulic presses and for long periods of time, the extreme simplicity of these pumps making it possible to supply them to the industry at a cost often less than half the cost of previously used high pressure pumps of similar capacity.

It is an object of the invention to provide a high pressure pump having a simple form of body which may be readily machined from a steel plate or forging, this body having all of the pump inlet and outlet passages, valve openings, and cylinder bores machined therein at comparatively low cost, the pump having simple valve units which may be easily removed for inspection and repair, these valve units, however, being of such form that they will operate for long periods of time without attention.

A further object of the invention is to provide a high pressure pump having a body with passages, openings and bores so arranged therein that they may be readily machined in the single body of metal from which the pump body is formed.

A further object of the invention is to provide in this high pressure pump a pump body having machined bores and inlet and outlet passages extending in spaced relation to these bores, such passages consisting of grooves, the outer portions of which are closed or filled with walls of metal fused or welded in place, the bottoms of these grooves then becoming continuous passages, and a further feature of the invention is to connect these passages with the cylinder bores by valve openings which are drilled into the body from the face thereof and are so formed that inlet and outlet check valves may be placed therein between the ports of communication of the openings with the cylinder bores and the communications between the openings and the inlet and outlet passages.

Further objects and advantages of the inven-

2

tion will be brought out in the following part of the specification.

Referring to the drawing which is for illustrative purposes only,

5 Fig. 1 is a face view of a pump embodying my invention.

Fig. 2 is a side view of the pump.

Fig. 3 is a fragmentary perspective view showing a portion of the pump body at one stage of its manufacture.

10 Fig. 4 is an enlarged section through a portion of the pump body at another stage of its manufacture.

Fig. 5 is an enlarged fragmentary sectional view taken as indicated by the line 5—5 of Fig. 1.

15 Fig. 6 is an enlarged fragmentary sectional view taken as indicated by the line 6—6 of Fig. 5.

The pump, as shown in Figs. 1 and 2, comprises a body 10 of metal such as steel or alloy, this body 10 having the form of a thick disc with a substantially central opening 11 forming a cavity in which the piston reciprocating means of the invention may be placed. The body 10 is secured by means of screws 12 to one end of a base 13 having bearings 14 and 15 for supporting a shaft 16 in concentric relation to the cavity 11, this shaft 16 having an eccentric 17 which projects into the cavity 11 and has thereon a roller or ball bearing 18, the outer race 19 of which engages the inner ends of pistons 20 to reciprocate such pistons as rotation of the shaft 16 causes the eccentric 17 to revolve around the axis of rotation of the shaft 16. The shaft 16 has a projecting end 21 to receive rotative force from a source of power.

20 As shown in Fig. 3, bores 22 to receive the pistons 20 are machined radially through the body 10 in spaced relation to the front of the body. In the pump structure shown in Figs. 1 and 2 there are four of these bores 22 to receive four pistons 20 disposed in 90° angular relation. The bores 22 are lapped to desired size and the outer ends of these bores 22 are threaded as shown at 23 to receive closures consisting of plugs 24.

25 Either before or after the bores 22 are machined, the body 10 is rotated in a lathe and grooves 24 and 25 are cut thereinto from the outer surface of the body, these grooves 24 and 25 being positioned so that the bottoms thereof will extend in closely spaced relation and in spaced relation to the bores 22. The grooves 24 and 25 may be cut into the body 10 in side by side relation from the front face thereof, or, as 30 shown in Fig. 3, one of the grooves may be cut

in from the peripheral face of the body 10 and the other of the grooves may be cut into the body 10 from the front face thereof. The grooves 24 and 25 are continuous and annular and the outer portions of these grooves are widened or flared so that metal strips 26 and 27, such as arcuate wires of round cross-section, may be placed in the outer portions of the grooves in spaced relation to the bottoms of the grooves, these metal strips 26 and 27, shown as bars of round cross section, close off the outer portions of the grooves from the inner or bottom portions thereof and are secured in place by metal fusion. In Fig. 4 I show welds 28 and 29 covering the strips 26 and 27; these welds 29 and 28 consist of bodies of metal applied either by use of gas or electric welding processes so that they are fused with the adjacent portions of the body 10 and effectively close off the outer widened portions of the grooves 24 and 25 so that the inner or bottom portions of the grooves 24 and 25 will remain as passages 30 and 31 in the body 10, such passages 30 and 31 being annular and extending in spaced relation to the bores 22.

Thereafter, pairs of valve openings are machined into the body 10 from the front face thereof. Each pair of valve openings is associated with a cylinder bore 22, and each pair of valve openings consists of a first valve opening 32 and a second valve opening 33 disposed as shown in Figs. 1, 5, and 6. The valve openings 32 and 33 are disposed on opposite sides of the cylinder bore 22 with which they are associated, and, as shown in Fig. 1, the valve openings 32 are placed at greater radial distance from the center of the body 10 than are the openings 33, so that the openings 32 will lie in crossing relation to the first passage 30 and the openings 33 will lie in crossing relation to the second passage 31. The inner ends 34 and 35 of the valve openings 32 and 33 are stepped or reduced in diameter so as to provide annular conical valve seats 36. The outer portions of the valve openings 32 and 33 communicate respectively with the passages 30 and 31, and between the seats 36 and the passages 30 and 31 the valve openings have internal threads 37. Outwardly from the passages 30 and 31 the outer ends of the valve openings 32 and 33 are provided with threads 38 to receive closure plugs 39.

The inner ends 34 and 35 of the valve openings 32 and 33 communicate with their associated cylinder bores 22 through ports 40 which are formed by use of small grinding wheels to remove a portion of the relatively thin metal wall of the body 10 existing between the inner ends 34 and 35 of the valve openings and the associated cylinder bores 22. It will be noted that the ports of communication 40 between the inner ends of the valve openings and the bores 22 are near the outer ends of the bores 22 which are closed by plugs 42 so that pumping chambers such as the space 43, Fig. 6, are formed in the bores 22 between the plugs 42 and the outer ends of the pistons 20.

As shown in Fig. 5, an inlet valve 44 is disposed in each valve opening 32 between its seat 36 and its point of communication with the passage 30. This inlet valve 44 comprises an externally threaded steel shell 45 having a valve seat 46 within its outer end and having a conical inner end 47 for sealing engagement with the seat 36 of the valve opening 32 when the shell 45 is screwed down tightly into place. A check valve ball 48 is urged into engagement with the seat 46 by a spring 49 which is held in place by a

transverse pin 50. Similarly, in each valve opening 33 there is an outlet valve 51 having an externally threaded shell 52, similar in external form to the shell 45 of the valve 44, so that the outlet valve 51 may be screwed down tightly against the seat 36 in the valve opening 33. The outlet valve 51 differs from the inlet valve 44 in having an internal seat 46' at its inner end, with a spring pressed ball 48' to cooperate therewith. When movement of the pistons 20 produces or permits enlargement of the pumping chambers, hydraulic fluid will flow inwardly from the passage 30 past the valve balls 48, and when the pistons 20 are moved so as to force fluid out of the pumping chambers 43, the valve balls 48 will close against the seat 46 and the hydraulic fluid must then pass out through the valves 51. External ducts for communication with the inlet and outlet passages 30 and 31 are provided by openings 55 and 56 drilled and tapped into the body 10 as shown in Fig. 1, the inner ends of these openings 55 and 56 communicating respectively with the passages 30 and 31. High pressure piping for the external circulation of the hydraulic fluid may be connected through these openings 55 and 56 with the passages 30 and 31, as exemplified by the piping 57 shown in Fig. 2 communicating through the threaded opening 55, this piping 57 ordinarily communicating with a reservoir in which oil is maintained at low pressure, for example, a pressure of 40 or 50 pounds. This pressure of oil is sufficient to act in the working chambers 43 to force the pistons 20 against the reciprocating means shown as the outer bearing race 19, thereby avoiding the necessity of employing springs or other means to move the pistons 20 through their return strokes. The outer ends of the valves 44 and 51 are provided with screw driver slots or wrench sockets whereby they may be rotated. Should the pump develop leakage as evidenced by a drop in capacity or pressure, the valves may be independently removed and inspected or tested.

I claim as my invention:

1. In a high pressure pump of the character described, the combination of: a pump body comprising an annular body of metal having a central cavity, said body having a pair of circular grooves extending in from the surface thereof, metal walls closing the outer portions of said grooves and being connected by fusion to the adjacent metal of said body, thereby making of the bottoms of said grooves first and second fluid tight passages, cylinder bores extending radially through said body in spaced and transverse relation to said passages to communicate with said cavity, inlet and outlet ducts extending in said body from the face thereof so as to communicate respectively with said first and second passages, a plurality of pairs of valve openings extending inward from the face of said body, there being a pair of said openings associated with each of said bores, each of said pairs of openings comprising a first opening in transverse relation to said first passage and communicating therewith and a second opening in transverse relation to said second passage and communicating therewith, each pair of said openings communicating with its associated bore at a point spaced from the point of communication of said openings with said passages; pistons operative in said bores; means in said cavity to reciprocate said pistons; a plurality of inlet and outlet check valves, said inlet check valves being disposed in said first openings between said bores and said first pas-

sages, and said outlet valves being disposed in said second openings between said bores and said second passages; and means to close and seal the outer ends of said openings.

2. In a high pressure pump of the character described, the combination of: a pump body comprising a body of metal having a central cavity, said body having a pair of grooves formed therein, the outer portions of said grooves being closed by annular walls of metal fused to said body, thereby making of the bottoms of said grooves first and second fluid tight passages, cylinder bores extending radially through said body in spaced and transverse relation to said passages to communicate with said cavity, inlet and outlet ducts formed in said body from the face thereof so as to communicate respectively with said first and second passages, a plurality of pairs of valve openings machined in said body, there being a pair of said openings associated with each of said bores, each of said pairs of openings comprising a first opening in transverse relation to said first passage and communicating therewith and a second opening in transverse relation to said second passage and communicating therewith, each pair of said openings communicating with its associated bore at a point spaced from the point of communication of said openings with said passages; pistons operative in said bores; means in said cavity to reciprocate said pistons; a plurality of inlet and outlet check valves, said inlet check valves being disposed in said first openings between said bores and said first passages, and said outlet valves being disposed in said second openings between said bores and said second passages; and means to close and seal the outer ends of said openings.

3. In a high pressure pump of the character described, the combination of: a pump body comprising a body of metal having a central cavity, said body having a pair of circular grooves extending in from the surface thereof, curved strips of metal placed in the outer portions of said grooves and secured by metal fusion with the adjacent portions of said body, making of the bottoms of said grooves first and second fluidtight passages, cylinder bores extending radially through said body in spaced and transverse relation to said passages to communicate with said cavity, inlet and outlet ducts extending in said body from the face thereof so as to communicate respectively with said first and second passages, a plurality of pairs of threaded valve openings in said body, there being a pair of said openings associated with each of said bores, each of said pairs of openings comprising a first opening in transverse relation to said first passage and communicating therewith and a second opening in transverse relation to said second passage and communicating therewith, each pair of said openings communicating with its associated bore at a point spaced from the point of communication of said openings with said passages; pistons operative in said bores; means in said cavity to reciprocate said pistons; a plurality of inlet and outlet check valves, said inlet check valves being disposed in said first openings between said bores and said first passages, and said outlet valves being disposed in said second openings between said bores and said second passages; thread means to secure said valves in said openings; and means to close and seal the outer ends of said openings.

4. In a high pressure pump of the character described, the combination of: a pump body comprising a body of metal having a central cav-

ity, said body having a pair of circular grooves extending in from the surface thereof, the outer portions of said grooves being widened, and curved strips of metal placed in the widened portions of said grooves and covered by welds fused with the adjacent portions of said body, making of the bottoms of said grooves first and second fluid-tight passages, cylinder bores extending radially through said body in spaced and transverse relation to said passages to communicate with said cavity, inlet and outlet ducts extending in said body from the face thereof so as to communicate respectively with said first and second passages, a plurality of pairs of valve openings in said body, there being a pair of said openings associated with each of said bores, each of said pairs of openings comprising a first opening in transverse relation to said first passage and communicating therewith and a second opening in transverse relation to said second passage and communicating therewith, each pair of said openings communicating with its associated bore at a point spaced from the point of communication of said openings with said passages; pistons operative in said bores; means in said cavity to reciprocate said pistons; a plurality of inlet and outlet check valves, said inlet check valves being disposed in said first openings between said bores and said first passages, and said outlet valves being disposed in said second openings between said bores and said second passages; and means to close and seal the outer ends of said openings.

5. In a high pressure pump of the character described, the combination of: a pump body comprising a body of metal having a central cavity, said body having a pair of circular grooves extending in from the surface thereof, metal walls closing the outer portions of said grooves and being connected by fusion to the adjacent metal of said body, thereby making of the bottoms of said grooves first and second fluidtight passages, cylinder bores extending radially through said body in spaced and transverse relation to said passages to communicate with said cavity, inlet and outlet ducts extending in said body from the face thereof so as to communicate respectively with said first and second passages, a plurality of pairs of valve openings in said body, there being a pair of said openings associated with each of said bores, each of said pairs of openings comprising a first opening in transverse relation to said first passage and communicating therewith and a second opening in transverse relation to said second passage and communicating therewith, each pair of said openings communicating with its associated bore at a point spaced from the point of communication of said openings with said passages, said openings being formed with annular shoulders between said bores and said passages so as to provide seats; pistons operative in said bores; means in said cavity to reciprocate said pistons; a plurality of inlet and outlet check valves placed in said openings respectively so as to engage said seats, said inlet check valves being disposed in said first openings between said bores and said first passages, and said outlet valves being disposed in said second openings between said bores and said second passages; and means to close and seal the outer ends of said openings.

6. In a high pressure pump of the character described, the combination of: a pump body comprising a body of metal having a central cavity, said body having a pair of circular grooves extending in from the surface thereof, the outer portions of said grooves being widened, and

curved strips of metal placed in the widened portions of said grooves and covered by welds fused with the adjacent portions of said body, making of the bottoms of said grooves first and second fluid tight passages, cylinder bores extending radially through said body in spaced and transverse relation to said passages to communicate with said cavity, inlet and outlet ducts extending in said body from the face thereof so as to communicate respectively with said first and second passages, a plurality of pairs of valve openings in said body, there being a pair of said openings associated with each of said bores, each of said pairs of openings comprising a first opening in transverse relation to said first passage and communicating therewith and a second opening in transverse relation to said second passage and communicating therewith, each pair of said openings communicating with its associated bore at a point spaced from the point of communication of said openings with said passages, said openings being formed with annular shoulders between said bores and said passages so as to provide seats; pistons operative in said bores; means in said cavity to reciprocate said pistons; a plurality of inlet and outlet check valves placed in said openings respectively so as to engage said seats, said inlet check valves being disposed in said first openings between said bores and said first passages, and said outlet valves being disposed in said second openings between said bores and said second passages; and means to close and seal the outer ends of said openings.

7. In a high pressure pump of the character described, the combination of: a pump body comprising a body of metal having a central cavity, said body having a pair of circular grooves extending in from the surface thereof, metal walls closing the outer portions of said grooves and being connected by fusion to the adjacent metal of said body, thereby making of the bottoms of said grooves first and second fluid tight passages, cylinder bores extending radially through said body in spaced and transverse relation to said

passages to communicate with said cavity, inlet and outlet ducts extending in said body from the face thereof so as to communicate respectively with said first and second passages, a plurality of pairs of valve openings in said body, there being a pair of said openings associated with each of said bores, each of said pairs of openings comprising a first opening in transverse relation to said first passage and communicating therewith and a second opening in transverse relation to said second passage and communicating therewith, each pair of said openings communicating with its associated bore at a point spaced from the point of communication of said openings with said passages, said openings being formed with annular shoulders between said bores and said passages so as to provide seats and being threaded between said seats and said passages; pistons operative in said bores; means in said cavity to reciprocate said pistons; a plurality of inlet and outlet externally threaded valve units placed in said openings respectively so as to engage said seats, said inlet valve units being disposed in said first openings between said bores and said first passages, and said outlet valve units being disposed in said second openings between said bores and said second passages; and means to close and seal the outer ends of said openings.
